UNITED STATES PATENT OFFICE.

EDGAR D. MISNER, OF DETROIT, MICHIGAN, ASSIGNOR, BY MESNE ASSIGNMENTS, TO LOVELL MANUFACTURING COMPANY, OF ERIE, PENNSYLVANIA, A CORPORATION OF PENNSYLVANIA.

WRINGER.

Application filed February 5, 1921. Serial No. 442,622.

To all whom it may concern:

Be it known that I, EDGAR D. MISNER, a citizen of the United States of America, residing at Detroit, in the county of Wayne and State of Michigan, have invented certain new and useful Improvements in Wringers, of which the following is a specification, reference being had therein to the accompanying drawings.

10 The invention relates to wringers and refers particularly to the power driven type. One object of the invention is to provide a wringer in which the pressure between the pair of rolls in frictional contact with each other, is predetermined and cannot be readily varied by the operator. Another object is the provision of equalizing means for facilitating the simultaneous and equal movements of the opposite ends of one of 15 the rolls from the other. Further objects of the invention reside in the novel features of construction and combinations and arrangements of parts as more fully herein-after set forth.

20 In the drawings:

Figure 1 is a side elevation partly in section of a wringer embodying my invention;

Figure 2 is a top plan view thereof;

Figure 3 is a central transverse cross section therethrough;

Figure 4 is a cross section on the line 4—4 of Figure 1;

Figure 5 is a side elevation of the top plate;

Figure 6 is a perspective view of a movable block.

Figure 7 is a fragmentary sectional view of a balancing means for the resilient upper roll holding member, and

Figure 8 is a sectional view through the top plate.

1 is the frame of the wringer formed of the complementary sections 2 and 3 which are suitably secured to each other as by 45 means of the bolts 4. 5 is the power driven roll and 6 the cooperating roll. The shaft 7 of the power driven roll is rotatably mounted in suitable bearing blocks 8 at its opposite ends and has the gear 9 at one end which is adapted to mesh with the gear 10 upon the shaft 11 of the cooperating roll. 12 are wooden bearing blocks impregnated

with lubricant and located at the opposite ends of the frame 1, these bearing blocks having the bearings 13 for engagement by 55 the shaft 11.

For moving the cooperating roll 6 toward and away from the power driven roll 5, there is the following construction: 14 is a resilient member extending above the co- 60 operating roll and having its opposite ends engaging between the straps 15 and the bearing blocks 12. 16 is a vertical shaft longitudinally movable in the top plate 17 which is secured centrally to the top of 65 the frame 1. This shaft is secured at its lower end to the clip 18 by means of the pin 19 engaging in the annular groove 20 in the shaft and extending transversely through the clip. The lower portion 21 of 70 the clip is U-shaped to embrace the resilient member 14. 22 are coil springs at opposite sides of the clip, connected at their lower ends to the projections 23 upon the clip and at their upper ends to suitable eye bolts 75 24 depending from the top plate 17. With this arrangement as thus far described, the shaft 16 is adapted to tension the resilient member 14 to press the cooperating roll 6 into frictional contact with the power 80 driven roll 5 while the coil springs 22 upon release of the shaft are adapted to retract the resilient member 14 to move the cooperating roll away from the power driven roll.

For the purpose of holding the cooperat- 85 ing roll 6 in frictional contact with the power driven roll 5, the shaft 16 has the transversely extending pin 25 near its upper end, which pin is adapted to pass through either of the pair of diametrically opposite 90 slots 26 in the top plate and to engage the lower faces of the lugs 27 between the pairs of slots upon slight rotation of the shaft. The lower faces of these lugs are preferably hollowed as at 28 to position the pin 25 95 and prevent accidental rotation of the shaft 16 and the consequent disengagement of the pin from the lugs. 29 is a handle above the wringer frame 1 and at the upper end of the shaft 16 by means of which the shaft 16 is moved inwardly to tension the resilient member 14 and press the rolls into frictional contact with each other and also by means of which the shaft is slightly rotated to 100

either engage the pin 25 with the lower faces of the lugs 27 or disengage the same.

In order to permit of easier engagement of the pin with the lower faces of the lugs, 5 their sides are under-cut as at 30, so that after the shaft 16 has been longitudinally moved inward so that the pin 25 can engage the under-cut sides, rotation of the shaft will force the pin to ride over the under-cut 10 sides and downwardly into engagement with the recesses 28 upon the lower sides of the lugs. With this arrangement it will be seen that the transversely extending pin is a stop for limiting the outward movement of the 15 shaft 16 and maintaining the resilient member 14 under tension to press the rolls in frictional contact with each other. To trip the mechanism and permit the coil springs 22 to operate, the shaft 16 can be slightly 20 rotated by swinging the handle 29 when the pin 25 will register with one pair of the slots 26.

For the purpose of preventing rotation of the handle 29 when moving away from the 25 top plate 17, each of the lugs 31 between the slots 26 has substantially vertical sides which extend above the lugs 27. This arrangement also facilitates the operator in 30 registering the pin 25 with the slots, since by moving the handle 29 downwardly until the pin 25 engages the top plate 17 and then rotating the handle, the sides of the lugs 31 will engage the pin at which time the latter is in registration with a pair of slots.

35 The sides of the complementary sections 2 and 3 of the wringer frame 1 have the vertical central bulging portions 32 in each of which there is the vertical groove 33. The clip 18 has the longitudinally extending 40 projections or keys 34 on its opposite sides which engage in the grooves 33 to guide the clip in its up and down movements.

To facilitate the simultaneous and equal 45 movements of the opposite ends of the cooperating roll 6 away from the power driven roll 5, the lower end of the shaft 16 is recessed as at 35 to receive the coil spring 35'. When the shaft 16 is in its innermost 50 position to tension the resilient member 14, the latter rests against the lower end of the shaft; but when the mechanism is tripped, the spring 35' will clamp the resilient member 14 against the base 36 of the U-shaped portion 21 of the clip to thereby 55 prevent rocking movement of the resilient member relative to the shaft. This resilient member is preferably formed with the lug 37 which is engageable within the 60 lower convolution of the coil spring 35' to longitudinally position the resilient member. The bearing blocks 12 also preferably have the sides 38 tapering to avoid too great a frictional resistance to their movements.

65 To limit the upward movement of the co-

operating roll 6 under the action of the coil springs 22, the flanges 39, which are upon the complementary sections of the frame and form the enlargement within which the cooperating roll moves, merge into the sides 70 of the sections above the cooperating roll and are adapted to be engaged thereby. These flanges are rounded and do not injure the roll.

To drain any moisture which drops off the 75 ends of the rolls, inwardly away from the ends of the wringer frame, the lower ends 40 of the flanges 39 extends beneath the ends of the power driven roll and are inclined inwardly.

80 The straps 15 are secured to the movable bearing blocks to reinforce and prevent splitting of the same as well as to secure the ends of the resilient member 14 thereto. Each bearing block is formed of wood impregnated with a lubricant and the grain of the wood extends longitudinally of the block and perpendicular to the axis of the hole or bearing 13 therein. The strap is of inverted U-shape and extends transversely of 85 the grain of the wood, so that its arms 41 embrace the layers of the block. These arms are secured to each other by suitable means such as the rivet 42 extending through the block; and preferably, the arms 90 are set into the sides of the block.

95 From the above description, it will be readily seen that I have provided a simple construction of wringer in which a predetermined pressure is applied to force the rolls into frictional contact with each other. This is due to the fact that the shaft 16 has a predetermined position relative to the power driven roll when the latter is in frictional contact with the cooperating roll. To 100 vary this compression, washers 43 between the top plate 17 and the top of the wringer frame may be added or removed, but this necessitates partial disassembly of the wringer.

105 What I claim as my invention is:

110 1. In a wringer, the combination with a frame, of a pair of rolls, bearings for one roll movable toward or from the other roll, a resilient member connected to said movable bearings to actuate the same toward or from said other roll, a longitudinally movable member slidably engaging said frame for tensioning said resilient member to press the rolls in frictional contact, a stop upon 115 said longitudinally movable member engageable with said frame to maintain said resilient member under tension, said longitudinally movable member being rotatable to disengage said stop from said frame, and coil springs connected to said resilient member to retract the same and separate said rolls from each other, upon disengagement of said stop from said frame.

120 2. In a wringer, the combination with the

- frame, of a pair of rolls, bearings for one roll movable toward or from the other roll, a resilient member connected to said movable bearings to actuate the same toward or 5 from said other roll, a clip embracing said resilient member, a vertical shaft longitudinally slidably engaging the top of said frame and connected to said clip, a transversely extending pin upon said shaft engageable with the under side of the top of 10 said frame, said shaft being rotatable to permit of disengagement of said pin from the frame top, coil springs at opposite sides of said clip for retracting the same with said 15 resilient member and movable bearing, and a resilient member upon said shaft engageable with said first named resilient member to clamp the same against said clip while being retracted. 20 3. In a wringer, the combination with a frame and a top plate thereon having a pair of diametrically extending slots with pairs of lugs therebetween, the sides of one pair of lugs being substantially vertical and the 25 sides of the other pair of lugs being under-cut, of a pair of rolls, a resilient member connected to one of said rolls for moving the same toward the other of said rolls, a longitudinally movable member slidably engaging said top plate and connected to said resilient member, and a transversely extending pin upon said longitudinally movable member adapted to pass through said pairs of slots in the top plate and to engage the 30 under-surface thereof. 35 4. In a wringer, the combination with a frame and a top plate thereon, having pairs of diametrically extending slots with pairs of lugs therebetween, the sides of one pair of lugs being under-cut, while the sides of the other pair of lugs are substantially vertical, said last-mentioned pair of lugs extending above the other pair of lugs, of a 40 pair of rolls, a resilient member for moving one of said rolls toward the other of said rolls, a longitudinally movable member slidably engaging said top plate and connected to said resilient member, a transversely extending pin upon said longitudinally movable member adapted to pass through said 45 slots, slidably contact with said under-cut sides and engage the under-surfaces of said pair of lugs having the under-cut sides, and a handle upon said longitudinally movable, 50 member above said top plate for moving said longitudinally movable member inward and for rotating the same. 55 5. In a wringer, the combination with a frame having spaced sides, of a pair of rolls, a resilient member connected to one of said rolls for moving said roll toward or away from said other roll, a longitudinally movable member slidably engaging said frame, a clip connecting said longitudinally movable member to said resilient mem- 60 ber, longitudinally extending projections at opposite sides of said clip, and grooves in said spaced sides engageable by said projections for guiding said clip in its movements toward and away from said other roll. 65 6. In a wringer, the combination with a frame and a pair of rolls mounted thereon, of a rotatable and longitudinally movable shaft for moving one of the rolls toward the other, means cooperating with said shaft upon rotation thereof for moving the shaft longitudinally thereof in one direction and holding the same in a predetermined position, said shaft being rotatable in either direction to release the same, and yieldable 70 means within said frame connected to said frame and shaft for moving said shaft longitudinally in the opposite direction when the same is released. 75 7. In a wringer, the combination with a frame and a pair of rolls mounted thereon, of a rotatable and longitudinally movable member for moving one of said rolls toward the other, a member cooperating with said first-mentioned member upon rotation thereof for longitudinally moving said first-mentioned member and holding the same in a predetermined position, one of said members having a step and inclined faces leading to said step, and the other of said members having a projection engageable with said step and faces, said first-mentioned member being rotatable in either direction to disengage said step and projection, and yieldable means within said frame connected 80 to the same and first-mentioned member for actuating the latter upon disengagement of said step and projection. 85 8. In a wringer, the combination with a frame, of a pair of rolls within said frame, one roll being movable toward or from the other roll, a yieldable member connected to said movable roll, an adjustable actuating member for said movable roll, means for holding said actuating member in adjusted position when moved in one direction, a member connecting said yieldable member to said actuating member, and yieldable means connected to the last-mentioned member and to said frame for moving said actuating member when released in the opposite direction from that in which the member is moved to bring it to adjusted position. 90 9. In a wringer, the combination with a frame, of a pair of rolls within said frame, one roll being movable toward and from the other roll, a yieldable member connected to said movable roll, an actuating member for said movable roll slidably engaging said frame, means for holding said actuating member in a predetermined position, a member loosely connecting said yieldable member to said actuating member, and yieldable means within said frame connected 95 100 to the same and first-mentioned member for actuating the latter upon disengagement of said step and projection. 105 110 115 120 125 130

to the last-mentioned member and to said frame for moving said actuating member when released.

10. In a wringer, the combination with a frame, of a pair of rolls, a resilient member connected to one of said rolls and adapted to move the same, a shaft connected to said member and adjustable to move the same and the roll connected thereto, a stop

10 upon said shaft engageable with said frame

to maintain said resilient member under tension, said shaft being rotatable to disengage said stop from said frame, and yieldable means connected to said resilient member to retract the same and separate the rolls 15 from each other upon disengagement of said stop from said frame.

In testimony whereof I affix my signature.

EDGAR D. MISNER.
